UNITED STATES PATENT OFFICE.

EUGENE LAFLEUR, OF MONTCLAIR, NEW JERSEY.

MATCH-STAND AND ASH-RECEIVER.

975,438.

Specification of Letters Patent. Patented Nov. 15, 1910.

Application filed February 28, 1910. Serial No. 546,364.

To all whom it may concern:

Be it known that I, EUGENE LAFLEUR, a subject of France, residing at Montclair, in the county of Essex and State of New Jersey, have invented certain new and useful Improvements in Match-Stands and Ash- Receivers, of which the following is a specification, reference being had to the accompanying drawings.

10 My invention relates to improvements in match stands and ash receivers, and consists in the novel features of construction and arrangement of parts hereinafter described in the claim.

15 The object of the invention is to provide a simple and practical device of this character which will not only support a box of matches, but also provide means for holding lighted cigars and cigarettes and receiving the ashes therefrom, the construction being such that the ashes will be effectively inclosed and prevented from being blown about on the table, or other support on which the device is placed.

20 25 The above and other objects are attained in the construction illustrated in the accompanying drawings in which:—

Figure 1 is a side elevation of my improved match stand and ash receiver; Fig. 2 is a top plan view; and Fig. 3 is a vertical section taken on the plane indicated by the line 3—3 in Fig. 1.

The invention comprises a body having a comparatively deep base section 1 to receive 30 and contain the ashes, and a removable top section 2 carrying a means for supporting matches and lighted cigars or cigarettes, and also having openings through which ashes may be deposited in the base section 35 or member 1. The latter is preferably of circular shape when viewed from the top and its surrounding side wall 3 is inclined or bowed transversely in an upward or inclined direction as shown. The upper edge 40 of the wall 3 is internally screw threaded as at 4 to receive an externally screw threaded flange 5 on a depending rim 6 which surrounds the top section 2, the latter being similar in shape to the base section. Rising 45

50 from the center of the top section or member 2 is a rigid standard 7 which carries at its top a holder 8 for a box of matches. Formed in the top section 2 on opposite sides of the standard 7 are elongated openings 9

through which the ashes are deposited into 55 the base section 1 of the device. Also formed in said top section 2 and extending in opposite directions from the openings 9 are depressions or grooves 10 in which burning or lighted cigars, cigarettes or the like may 60 be placed with their ignited ends disposed over the openings so that the ashes will drop on to the bottom of the base section 1. By constructing the top section in this manner it will be seen that four cigars or the like 65 may be supported so that the ashes will drop into the device, and the ashes of a cigar held in the hand may be readily knocked off into one of the openings 9 so that they will fall and collect upon the bottom of the base section 2. The two sections effectively inclose the ashes so that they can not possibly be blown about the room, and at the same time the screw threaded or detachable two sections of the device enables 70 them to be easily separated to remove the ashes and to clean the base section. It will be noted that the match box holder 8 and standard 7 will serve as a handle for the upper section 2, and hence for the entire 75 device.

Having thus described the invention, what is claimed is:

The herein described device comprising a circular base section having an upwardly 85 and inwardly inclined surrounding wall formed with an internally screw-threaded, inwardly-extending rim, a flat top section having a depending annular flange with an externally screw threaded portion to screw 90 into said rim on the upright wall of the base section, the flat top section being formed on opposite sides of its center with elongated openings and with cigar receiving channels or seats stamped in the same at opposite ends 95 of and communicating with said elongated openings, the center of said top section being formed with a standard having a reduced screw threaded stem at its top and a match box holder arranged on said screw threaded 100 stem to serve as a handle for the device.

In testimony whereof I hereunto affix my signature in the presence of two witnesses.

EUGENE LAFLEUR.
